UNITED STATES PATENT OFFICE.

WILLIAM KEATS AND JOHN KEATS, OF STREET, ENGLAND.

IMPROVEMENT IN THE MANUFACTURE OF BOOTS AND SHOES.

Specification forming part of Letters Patent No. 72,045, dated December 10, 1867; patented in England, April 14, 1863.

To all whom it may concern:

Be it known that we, WILLIAM KEATS and JOHN KEATS, both of Street, in the county of Somerset, England, subjects of the Queen of Great Britain, have invented or discovered new and useful Improvements in the Manufacture of Boots, Shoes, or other Coverings for the Feet; and we, the said WILLIAM KEATS and JOHN KEATS, do hereby declare the nature of the said invention, and in what manner the same is to be performed, to be particularly described and ascertained in and by the following statement thereof—that is to say:

This invention has for its object improvements in the manufacture of boots, shoes, or other coverings for the feet.

In manufacturing boots, shoes, or other coverings for the feet according to this invention, the edge of the sole has a strip cut from its under side all round its edge, so as to leave all round the upper edge of the sole a strip of less thickness than the rest of the sole. To this thin strip the edge of the upper, previously cut to the required shape, is sewed, the outer face of the upper being toward the outer face of the sole. The upper and sole are then turned inside out. The boot or other covering for the feet may then be finished as though the upper had been connected to the sole in the usual way. In addition to the sole being cut as above described, so as to leave a thin strip around its edge, we prefer to enlarge the strip by cutting, with a suitable tool, a slit into the edge of the sole, just below the bottom or under side of the strip.

Referring to the drawings, Figure 1 is a section of a sole prepared according to the method described. Fig. 2 is a plan view of the same in course of preparation. Fig. 3 is a cross-section, showing the sole and the upper as first connected together; and Fig. 4 is a cross-section of the same when turned inside out. Fig. 5 is a sectional elevation of a boot when completed.

In order to cut the sole in the manner shown at Figs. 1 and 2, we prefer to proceed as follows: The sole, which has first been cut to the required shape, is moved past two stationary knives, one of which forms the slit into the edge of the sole, and the other makes a cut

at right angles thereto, and severs off a strip, C, as seen at Fig. 2, thus leaving a thin strip, D, all round the edge of the sole. The strip C is taken off from the grain side of the leather.

In order to move the edge of the sole past the cutters, and to insure the edge being properly cut by them, the edge of the sole is by hand held against a stop that projects up from a table on which the sole rests. This stop is arranged to carry the cutter that makes the slit into the edge of the sole. Close to this cutter, and above the sole, is a spring or presser, that presses down the sole onto the table. Pressing on the upper surface of the sole is also a revolving serrated wheel, by which the sole is moved forward past the cutters; and as the sole is so moved past the cutters, the edge of the sole is, as before mentioned, kept by hand against the stop. When the sole has thus been brought to the requisite shape, the strip D, that is left all round it, is connected by sewing to the outer edge of an upper, B, that has first been cut to the requisite shape.

In order to obtain a suitable pattern from which to cut out what is known as the "base" of the upper, we first stretch canvas or other material, that is first cut nearly to the requisite shape, over a last of the form of the boot to be made. The canvas stretched over the last is cut around the last, leaving a sufficient margin for the seam. Two pieces of canvas, one for each side of the boot, are thus shaped. From these pieces of canvas patterns of like form are constructed, the patterns being, by preference, made of sheet metal. The leather or other material which is to form the base of the upper is cut to the shape of these metal patterns, and the two parts of the base are connected together, and upon them are also applied covering-pieces of leather, which are to form the outer surface of the upper, as is usual. The outer edge of the upper so prepared is connected to the sole by sewing, as above described. The upper and sole are then turned inside out. The heel of the boot may then be formed by pegging or riveting on lifts and top pieces, as shown at K, Fig. 5. A stiffener, H, may also be inserted between the base and the outer portions of the upper before turning

the boot inside out, and after the boot has been turned inside out the stiffener is secured by rivets, as at I.

Having thus described the nature of our invention, and the manner of performing the same, we would have it understood that what we claim is—

The construction of coverings for the feet, substantially as hereinbefore set forth—that

is to say, with the sole cut at the edge, and sewed to the edge of the upper while turned outward, substantially as described.

WILLIAM KEATS.
JOHN KEATS.
